F. R. WOLTER

MOP PAIL AND WRINGER

Filed June 8, 1922

INVENTOR.
FERDINAND R. WOLTER
BY HIS ATTORNEY.

James F. Williamson

UNITED STATES PATENT OFFICE.

FERDINAND R. WOLTER, OF MINNEAPOLIS, MINNESOTA.

MOP PAIL AND WRINGER.

Application filed June 8, 1922. Serial No. 566,688.

To all whom it may concern:

Be it known that I, FERDINAND R. WOLTER, a citizen of the United States, residing at Minneapolis, in the county of Hennepin and State of Minnesota, have invented certain new and useful Improvements in Mop Pails and Wringers; and I do hereby declare the following to be a full, clear, and exact description of the invention, such as will enable others skilled in the art to which it appertains to make and use the same.

This invention relates to a mop pail and wringer device therefor. Such devices are now extensively used and usually comprise a liquid holding pail or receptacle and a wringer device at the top thereof comprising relatively movable rollers between which the mop is squeezed after being rinsed or dipped in the pail.

It is an object of this invention to provide such a device having a fixed or local roller and a movable roller movable toward the fixed roller in a downwardly inclined direction to more efficiently squeeze the mop.

It is a further object of the invention to provide a track or cam means for guiding the movable roller toward and from the fixed roller, which means comprises a downwardly extending portion adjacent the fixed roller. It is still another object of the invention to provide mop guiding means or guards which are shaped to conform to the contour of said track or cam means.

These and other objects and advantages of the invention will be fully set forth in the following description made in connection with the accompanying drawings in which like reference characters refer to the same parts throughout the different views, and in which,

Fig. 1 is a view in side elevation of the device;

Fig. 2 is a top plan view thereof;

Fig. 3 is a vertical section taken on the line 3—3 of Fig. 1, and shown on an enlarged scale; and

Fig. 4 is an end view of one of the rollers partly in section also shown on an enlarged scale.

Referring to the drawings, the device comprises a pail or liquid holding receptacle 1. While this pail may be of any desired shape, the same is illustrated as being substantially rectangular or square in cross section and is provided at its top edge with a rolled wire containing bead. This pail has

a bail 2 secured to and extending along the sides thereof at the bottom, said bail having a forwardly projecting portion 3 adapted to contact with the floor or supporting surface for the pail. The bail 2 is provided with an outwardly bent portion substantially centrally of the sides of the pail 1 which is spaced slightly from the pail, which portion is adapted to hold foot plates 4 having U-shaped side portions adapted to hook over the side of the bail and be disposed between the same and the sides of the pail.

Straps 5 are provided at the tops of the sides of the pail and are secured at one end to plates 6 disposed at the outside of and secured to the pail sides, which plates have horizontal portions extending over the sides to which the straps 5 are attached. These straps are formed with loops or eyes at their forward ends forming the bearings for the end journals of the fixed or local roller 7. The straps 5 extend in a horizontal rearwardly direction a short distance from the roller 7 and then extend upwardly in a rearwardly inclined direction and are curved to again extend downwardly to the rear of the pail and which are secured to the inside thereof. A movable roller 8 has projecting end journals extending across the top of the straps 5 and small U-shaped clips 9 extend under the straps having ears projecting upwardly at the sides thereof apertured to receive the journals of the roller 8. Journals are thus held substantially in contact with the straps 5 which form tracks therefor. Rigid arms 10 extend across the ends of the journals of the roller 8 and have their upper ends curved to extend over the tracks 5 and clips 9, said ends extending downwardly and being apertured to receive the journals of the roller 8 adjacent the ends of said roller.

The arms 10 extend along the outside of the pail and are pivoted at their other ends to the outside of the treadle bail 11 which embraces the sides of the pail and extends forwardly thereof where it is provided with a treadle plate 12. The pail has angle plates 13 secured thereto at the rear corners thereof adjacent its top and said plates are provided adjacent their lower ends with pressed-out conical portions 14 adapted to receive the heads of pivot bolts 16 on which the ends of the bail 11 are pivoted and on which they are held by suitable nuts.

applied to said bolts. Coiled springs 17 are secured to the plates 13 adjacent the tops thereof and attached at their other ends to the treadle bail 11 adjacent its pivotal points.

A pair of mop guiding members or guards 18 are provided and secured to the inner sides of the pail at the rear and top thereof and are extended forwardly to the front side of the pail to which their inturned ends are bolted. These guards are shaped to conform to the contour of the tracks 5, being spaced somewhat below the same. The pail 1 is provided with attaching ears 15 at its sides to which is pivoted a handle carrying bail 19.

The rollers 7 and 8 are preferably formed of pressed sheet metal tubing, as shown in Fig. 4, the ends of which are crimped and 20 clamped to the disks 20 carrying the projecting journals 21.

In operation, the springs 17 hold the bail 11 normally elevated, as shown in Fig. 1, and the arms 10 will then be inclined rearwardly and the roller 8 held in position adjacent the rear of the pail or at the side thereof opposite the roller 7. When it is desired to squeeze the mop, the same will be inserted in the top of the pail between 30 the members 18. The foot will then be placed upon the plate 12 and treadle bail 11 depressed to substantially the position shown in dotted lines in Fig. 1. If desired, the other foot can be placed upon one of the 35 foot plates 4 when the bail is so pressed. When the bail 11 is pressed downwardly the arms 10 cause the roller 8 to move toward the roller 7 and to follow the contour of the tracks 5. The roller is thus first elevated 40 and is then moved downwardly as it approaches the fixed roller 7 so that a downward squeezing pressure is exerted on the mop. This downward squeezing pressure acts very efficiently to squeeze the water and 45 dirt from the mop, and produces a wedging action of the rollers. The movable roller is not only moved downwardly but is cammed forwardly by tracks 5, thus giving a very 50 effective action. The arms 10 being connected near the front of bail 11, a great leverage is obtained, giving a heavy pressure on the rollers. When the pressure on the treadle bail 11 is released the parts resume 55 their normal position shown in full lines in Fig. 1. The projecting bail 2 acts to stabilize the pail and prevent overturning of the same by pressure applied to the bail 11.

From the above description it is seen that applicant has provided a simple and inexpensive mop pail and wringer and one which acts very efficiently to squeeze the mop. The parts of the device are all easily made from standard material which can be easily obtained.

It will, of course, be understood that vari-

ous changes may be made in the form, details and arrangement of the parts without departing from the scope of my invention, which, generally stated, consists in the matter shown and described and set forth in the appended claims.

What is claimed is:

1. A mop pail and wringer device having in combination, a pail, a local roller journaled at the top edge thereof adjacent one side of the pail, spaced parallel rails extending substantially horizontally from said local roller then upwardly and then downwardly to the opposite side of said pail, a movable roller, axially extending journals at the ends thereof, an arm extending across the end of each of said journals at one side of said rails and having its ends bent parallel to said arm and apertured to receive each of said journals at the other side of each of said rails, U-shaped clips secured to said journals and extending under said rails, and means including a treadle bail to which the free ends of said arms are connected for moving said movable roller and clips along said rails.

2. A mop pail and wringer device having in combination, a pail, a local roller journaled at the top edge thereof adjacent one side of the pail, spaced parallel rails extending substantially horizontally from said local roller then upwardly at a comparatively steep angle and then downwardly at a smaller angle to the opposite side of said pail, a movable roller having axially extending journals at the ends thereof, arms at each side of said pail in which said journals are disposed, and swinging means connected to said arms for moving said movable roller on said rails into close proximity to said local roller.

3. A mop wringer device having in combination, a pail, a local roller journaled against the top and front side thereof, a movable roller normally disposed adjacent the rear and top of said pail, a U-shaped bail extending around the front of said pail and having its ends pivoted at the sides thereof at a point substantially beneath the normal position of said movable roller, links pivoted to each side of said pail and to the ends of said movable roller forming the sole connection to said movable roller, tracks secured to the top of said pail at each side on which said movable roller is guided, said tracks extending upwardly from the rear of said pail, then downwardly on a line passing inside of and below said local roller and then horizontally below the center of said local roller.

4. A mop wringer device having in combination, a pail, a local roller journaled at one side and adjacent the top thereof, tracks secured along the top of the sides of said pail having loops at one end forming bear-

ings, said local roller having its journals mounted in said bearings, said tracks extending horizontally a short distance from said loops then extending upwardly and being curved to extend downwardly and secured at the rear of said pail, and a movable roller guided by said tracks.

5. The structure set forth in claim 4, **U**-shaped clips extending beneath said tracks having ears projecting upwardly at the sides

thereof receiving journals extending from said movable roller, arms extending along the outside of the pail having their upper ends curved inwardly and downwardly and receiving the journals of the movable roller, 15 and a treadle bail pivoted at one end outside of the pail to which said arms are pivoted.

In testimony whereof I affix my signature.
FERDINAND R. WOLTER.
